UNITED STATES PATENT OFFICE.

HENRY R. STEVENS, ROBERT L. ROCKWELL, AND ERNEST G. HOWE, OF SEATTLE, WASHINGTON, ASSIGNEES, BY MESNE ASSIGNMENTS, TO ROYAL A. McCLURE, JESSE N. BLALOCK, ALBERT E. HOLLAND, DAVID O. McCLAY, AND ERNEST G. HOWE, ALL OF SEATTLE, WASHINGTON, TRUSTEES.

ELECTRICAL CONTROL SYSTEM FOR OPERATING RAILWAY TRACK SWITCHES, DRAW SPANS, TURNTABLES, AND THE LIKE.

1,410,844.

Specification of Letters Patent. Patented Mar. 28, 1922.

Application filed June 12, 1918. Serial No. 239,677.

To all whom it may concern:

Be it known that we, HENRY R. STEVENS, ROBERT L. ROCKWELL, and ERNEST G. HOWE, citizens of the United States, residing at 5 Seattle, in the county of King and State of Washington, have invented a new and useful Improvement in Electrical Control Systems for Operating Railway Track Switches, Draw Spans, Turntables, and the 10 like, of which the following is a specification.

This invention relates to improvements in electrical control systems for operating railway track switches, draw spans turntables and the like, and the object of this 15 improvement is to provide a reliable and efficient electrical control system which may be set in operation by the closing of an electric circuit and which will then operate 20 automatically to unlock, move and lock any desired piece of mechanism, as for instance a switch, turntable or draw span.

The invention is herein shown as applied to a monorail track switch, a monorail turntable and a cantalever bridge span of a form more thoroughly disclosed in United States Patents No. 1,286,042 covering improvements in railway track switches, issued to Universal Elevated Railway Company Nov. 26, 1918, and No. 1,326,362, covering improvements in turntables, issued to Universal Elevated Railway Company April 6, 1920, but it will be understood that this 35 control system is equally well adapted for use with various other forms of mechanism where the same or a similar series of operations are to be performed.

In the accompanying drawings, Figure 1 is a wiring diagram illustrating the invention, and Figs. 2, 3 and 4 are diagrammatic views illustrating one manner of applying the invention to a switch, a turntable, and a cantalever bridge respectively. Fig. 5 is a sectional side elevation of the latch motor limit switch showing the method of actuating the switch by means of a rod connected to the movable section lock bolt. Fig. 6 is an enlarged fragmentary plan view of the limit switch to more clearly show the 50 method of mounting and actuating the

ratchet wheel element, and its relation to the switch members and ball race casting.

This control system, when applied to a track switch, turntable or bridge span, the sequence of operation at the closing switch 55 is as follows: The first operation unlocks a movable track section from an initial position; the second operation swings the movable track section to a new position; the third operation locks the track section in 60 the new position; the closing of another switch starts a series of operations that unlock the movable section, swings it back to the initial position and locks it in the initial position.

Referring to the drawings, throughout which like reference numerals indicate like parts, the numerals 1 and 1' Fig. 2, indicate the main rails of a single rail track, and 2 indicates a turnout or siding rail that 70 branches off from the main track.

3 and 4 indicate two switch rail sections that are secured to each other and pivoted, as at 5, so that they will be moved from the position shown by full lines to the position 75 shown by broken lines to selectively establish connection between the two main line rail sections 1 and 1' or between the main rail section 1 and the siding rail section 2.

The purpose of this invention is to provide an automatic electric control system that will enable the motorman as he approaches the track switch to close an electrical contact and set in motion machinery 85 that will unlock the switch members 3 and 4, swing them to a new position and lock them in the new position.

Fig. 2 illustrates the same system as applied to a turntable 6 that may be interposed in the track line between two main line rail sections 7 and 7' and two cross line rail sections 8 and 8' and operated by the closing of a switch to unlock the turntable, swing it through an angle of 90° and lock it 95 in the new position.

Fig. 4 illustrates the same system as applied to a cantalever span 9 that may be interposed between two rail sections 10 and 10'.

Throughout the following description it 100

will be assumed that the control system is applied to the switch shown in Fig. 2 and it is thought that the description of the system as thus applied will make clear its operation as applied to the turntable and cantilever span. For convenience, the different circuits are hereinafter designated by numbers and letters.

Referring to Figs. 1 and 2, let it be assumed that the switch members 3 and 4 are in the position shown by full lines and that it is desired to move such switch members into the position shown by broken lines to permit a car 11 to pass to the siding track 2 and then to move the switch members back into the position shown by full lines.

The car 11 is provided with the usual trolley-pole 12 that is connected by wires 13 and 14 and switch 15 with a contact shoe 16 that is adapted to make contact with an insulated rail section 17 located near the track 1 at a short distance from the switch sections 3 and 4.

As the car 11 approaches the switch, the operator will bring such car to a stop with the shoe 16 in contact with the insulated rail section and to throw the track switch formed by the rail sections 3 and 4 he would close the electric switch 15 which may be so arranged that it is mechanically interlocked with the controller for the car, drawing motors and the main air valve so that it is impossible to close such switch unless the current to the driving motors is turned off and the brake set, thus insuring a complete stopping of the car before the switch is closed.

Upon closing the switch 15, current will flow from the trolley wire 18, Fig. 1, through trolley pole 12, connecting wire 13, switch 15, connecting wire 14, contact shoe 16, insulated rail section 17, wire 19, current limited resistance 20, relay solenoids 21 and 22 connected in parallel, wire 23 to terminal 38, thence through wire 25 and solenoid 26 to wire 27, which is permanently connected to track section 1 and back to the source of supply. (Call this circuit 1.)

This flow of current energizes solenoids 21 and 22 which raise the iron plungers 21' and 22' respectively, closing contacts 28 and 29. The closing of these contacts completes two other circuits, one of which, circuit 2, is from positive terminal 30, through wires 31, 32 and 33, contact 28, wire 34, switch blade 35 of limit switch 36, blade 37, wire 24, solenoids 21 and 22, and wire 23 to negative terminal 38, thus holding closed the contacts 28 and 29 after the current has once been sent through them by closing the switch 15. The other circuit referred to, and herein designated as circuit 3, is from the positive terminal 30, through wires 31, 32 and 33, contact 28, wire 34, blades 35, wire 39, field magnet winding 40, and armature 41 of the latch operating motor, which is of comparatively

small size, then through switch blade 42, wire 43, contacts 29 and wire 23 to the negative terminal 38.

This current thus flows through the circuit and drives the latch operating motor in such a direction as to throw a bolt 41', unlock the switch which requires a predetermined definite number of revolutions of the motor. At the end of the number of revolutions the limit switch 36 is thrown to the right, by means of rods 41" attached to lock bolt 41'. A quick break at contacts 44 and quick connection with contacts 45 is insured by means of ball race casting 13' and ball 13" mounted separate from the switch blades 35, 37 and 42, on switch base 12'. In unlocking the track section, rod 41" carrying pin 41''' engages the forked projection 13''' and carries the ball race casting to the right until its radial center line passes the vertical center line of the limit switch. Ball 13" then rolls to the other end of the ball race of casting 13' which engages the elevated ends of the bent switch blades 35, 37 and 42 and drives them into contact jaws 45. It is evident that when the switch blades 42, 37 and 35 leave contacts 44, both circuit 2 and circuit 3 are opened which allows plungers 21 and 22 to fall, thus breaking the circuits at contacts 28 and 29, which in turn also opens the circuits 2 and 3, as both include contacts 28. It is also evident that these circuits are not again completed when the switch blades 42, 37 and 35 close the contacts 45.

Referring to Figs. 5 and 6 in addition to Fig. 1, contact finger 46 is mounted on a projection 13'' cast integral with the ball race casting 13' which has suitable journals (not shown) straddling switch blade 37 and carried in bearings (not shown) mounted on base 12' of suitable insulating material. This construction permits the ball race casting 13' together with contact finger 46 to be rotated through an angle of 90 degrees about the center of ratchet wheel 48 against which contact finger 46 is held by spring 49 also secured to ball race casting 13'. Wires 32 and 33 of Fig. 1 connect to the bearings (not shown) supporting ball race casting 13' which in turn makes connection with contact finger 46. Insulation sections 47, 47', 47'' and 47''' are placed in slots in metallic ratchet wheel 48 which is supported by the spindle projection 50' made integral with pedestal casting 50 which in turn is secured to switch base 12' by means of screws 17''.

The ratchet projections of pedestal casting 50 meshing with similar projections from the hub 48' prevent the rotation of ratchet wheel 48 in a clockwise direction, but by compressing spring 49' against washer 16' held in place by nut 15' it is allowed to rotate in a counter clockwise direction.

When ball race casting is thrown to the right by the movement of rod 48" in the di-

rection of the arrow, Fig. 5, and the switch blades 35, 37 and 42 make contact with jaws 45, contact finger 46 is drawn in a clockwise direction from insulation section 47 to insulation section 47', the ratchet wheel remaining stationary. During the movement of the contact finger an electrical contact is made between finger 46 and ratchet wheel 48, which closes another circuit which we call circuit 4 that starts the track switch motor 51.

With finger 46 in contact with ratchet wheel 48, current flows from the positive terminal 30, through wires 31 and 32, finger 46, ratchet 48, wire 52, current limiting resistance 53, contactor magnet coil 54, wire 65, contacts 117, wire 55, contact fingers 56, contact segments 57 on track motor limit switch 36 to contact finger 58, thence through wire 59 to the negative terminal 38.

Magnet coil 54 closes contactors 60 and 61 which operate together because of the mechanical connection through a bar of electrical insulating material 62. The closing of these contactors completes another circuit through magnet coil 54, which will be referred to as circuit 5 and which is as follows:

From the positive terminal 63, through wire 64, magnet coil 54, wire 65, contacts 117, wire 55, contact finger 56, contact segment 57, contact finger 58, and wire 59 to negative terminal 38, thus keeping the contactors 60 and 61 closed after being once closed by current flow through circuit 4.

A mechanical brake is provided which is attached to the shaft of the track switch motor, being kept normally in the operative condition by means of heavy springs, an electromagnet, usually of the ironclad plunger type, is so connected mechanically to the brake mechanism that when the magnet is energized the resultant movement of the plunger releases the brake and allows the motor to turn freely. The brake sets again as soon as current ceases to flow through the releasing magnet.

Whenever contactors 60 and 61 are closed, current flows from terminal 63 through wires 68 and 80, brake magnet coil 81, wires 82, to negative terminal 83, thus releasing the brake.

A circuit hereinafter referred to as circuit 6^a is formed by the closing of contactors 60 and 61 which energizes also two of the motor armature reversing contactor magnets 66 and 67 by means of the circuit from the positive terminal 63, through wire 68, contact finger 69, contact segment 70, contact finger 71 and wire 72 to a point 73 where the circuit divides between points 73 and 74 as follows: The first branch from the point 73 passes through wire 75, into lock contact 76, wire 77 and magnet coil 67, which closes contactor 78 to point 74.

The second branch passes from the point

73, through wire 79, into lock contactors 84, wire 85, magnet 66, which closes contactor 86 and wires 87 and 88 to point 74. From the point 74 the circuit is through wires 89, 90 and 91, to negative terminal 83.

70

With contactors 60, 61, 86 and 78 closed, the track switch motor will rotate in the proper direction to throw the track switch, the flow of current being from the source of supply through trolley wire 18, which is tapped by wire 92, through solenoid 93, wire 94, contactor 60, wires 95 and 96, solenoid 97, wire 98, solenoid 99, wire 100, solenoid 101, wire 102, grid resistor sections 103, 104, 105 and 106, wires 107 and 108, contactor 86, wire 109, interpole winding 110, and armature 51, of the track switch motor; thence through wire 111, contactor 78, wires 112 and 113, series field winding 114, wire 115, contactor 61, wire 25, solenoid 26 and wire 85 27, which connects with the track through which the current flows back to the source of supply, thereby forming a circuit herein-after referred to as circuit 7^a.

80

It is evident that circuit 7^a includes all of the grid resistor sections when current is first turned into the motor. As the armature speed increases, it is necessary to cut out these sections one at a time, at the same time keeping the current in the circuit within a prescribed limit. This is accomplished by means of contactors 118, 119, 120 and 121, which close in the order named. The operation of the central circuit will be better understood by noting that:

90

1st. Contactors 60, 118, 119 and 120 hold their respective plungers 122, 123, 124 and 125 in raised positions so that contacts 126, 127, 128 and 129 respectively are broken. The weight of the plungers and the design of the solenoids are such that if the motor current exceeds the predetermined value previously mentioned the solenoids will hold the plungers away from the contacts, if the plunger is in that position when the current is turned on, but the strength of the solenoids is not sufficient to raise the plungers after they have dropped down, due to the decrease in current value, even if the current be increased again to its initial value.

100

2nd. The contactors referred to, by means of the projections 130, 131, 132 and 133 respectively hold up their respective plungers within the solenoids as long as the contactors are open, but upon closing any one of the contactors the respective plunger is prevented from falling only by the attractive action of the solenoid energized by the motor circuit current.

110

3rd. The disk interlocks 134, 135, 136 and 137 are mechanically operated by contactors 86, 138, 78 and 139, respectively by means of their respective projections 140, 141, 142 and 143. In each case the top set of disk contacts are closed when the

120

125

130

contactor is open, and the top set opened and the bottom set of disk contacts closed when the contactor is closed.

When contactors 60, 61, 86 and 78 are first closed, the rush of current through the current limiting relay 93 is sufficient to hold plunger 122 in its original position although the projection 130 would then allow it to close. As the armature 51 gains speed, and the current decreases to the prescribed limit, plunger 122 drops, closing contacts 126, which completes a circuit hereinafter designated as circuit 8.

From positive terminal 63, through wire 68, contact finger 69, wire 144 and 145, contact 146, wire 147, contacts 148, wires 149, 150 and 151, contacts 126, wire 152, contactor magnet coil 153, wires 154, 155, 156 and 91, to negative terminal 83. This includes only the first branch.

Magnet coil 153 closes contactor 118, which it will be noted short circuits wire 102 and grid resistor 103 out of circuit 7^A, thus increasing the flow of current in the circuit again so that solenoid 101 prevents the closing of contacts 127 until the current again decreases to the prescribed limit.

The first branch of circuit 8 consists of wire 151, contacts 126, wire 152, and magnet coil 153.

As the armature 51 gains more speed and the current through the solenoid 101 decreases, plunger 123 drops, closing contacts 127, which allow current to flow through the second branch of circuit 8, consisting of contacts 127, wire 157, and magnet coil 158, which closes contactor 119, which short circuits sections 100, 101, 102, 103 and 104 from circuit 7^A, and again brings current above the prescribed limit. When the current again decreases, it allows plunger 124 to drop, thus completing the third branch of circuit 8, which comprises contacts 128, wire 159 and magnet coil 160. This closes contactor 120, which short circuits sections 98, 99, 100, 101, 102, 103, 104 and 105 of circuit 7^A, and again brings the current in that circuit above the prescribed limit.

When the speed of the armature comes up to its rated value, and the current again decreases, thereby allowing plunger 125 to fall, the fourth branch of circuit 8 is completed. This consists of contacts 129, wire 161 and magnet coil 162, which closes contactor 121, which short circuits sections 96, 97, 98, 99, 100, 101, 102, 103, 104, 105, and 106 of circuit 7^A, thus connecting the motor directly across the terminals 63 and 83 and applying full line voltage.

After the motor has completed sufficient revolutions to swing the curved switch section 4, Fig. 2, so as to engage the main track section 1, the limit switch is thrown quickly so contact segments 163 and 164 make contact with contact fingers 58, 56, 69

and 165. Contact segments 57, 70 and 166 would then appear to the right of the row of contact fingers in the diagram of Fig. 1.

This movement of the limit switch opens control circuits 5, 6^A and 8, which allow all previously closed contactors to open motor circuit 7^A and in addition opens the motor brake solenoid circuit, allowing the brake to bring the motor to a quick stop. It will be noted that these circuits are not closed completely again when the new set of connections are made between the contact segments and fingers of the limit switch; but again require the closing of contactors 60 and 61, which in turn requires the closing of circuit 4 through the contact fingers 46 and ratchet wheel 48, hence requires operation of the latch motor in the direction for opening the latch before the track switch motor can again be operated.

It will be noticed that when the track switch motor actuates the limit switch in either direction, a momentary contact will be made between the contact fingers 167, 168, and contact segments 166. This completes circuit 9 from terminal 30 through wires 31 and 169, contact finger 167, contact segment 166, contact finger 168 and wire 170, current limiting resistance 171, solenoids 21 and 22 in parallel, wire 23 to negative terminal 27; thus it is seen that this is equivalent to closing circuit 1, which in turn closes circuit 2 and 3, but it must be borne in mind that we now have blades 42, 37 and 35 of the limit switch closed with contactors 45, hence field coil 173 instead of field coil 40 will be included in circuit 3, and the latch motor will operate in the reverse direction, closing the latch which holds the track switch firmly in position.

At the limit of travel of the latch bolt 41', Fig. 2, the limit switch 36 is thrown again to its original position, opening circuits 2 and 3 and stopping the motor. This movement of the limit switch turns ratchet wheel 48 in a counter clockwise direction, so insulation segment 47' will then occupy the position shown in the diagram for insulation segment 47. In doing this, finger 46 does not make electrical connection with ratchet wheel 48, hence the track switch motor control circuit is not energized and both motors are disconnected from the lines, thereby completing the cycle of operation required to unlock the track switch, swing it in one direction and lock it again.

With the track switch connecting track sections 1 and 2, car 11 would then be run onto section 2 and again stop so contact shoe 16 would make connection with the insulated rail section 70 with controller at the "off position" and brakes set the motor man would swing the track switch back to its original position, thus opening the main line track by again closing push but-

ton switch 15, which, as has been shown, completes circuit 1, which in turn closes circuit 2 and 3 by means of the relay contacts 28 and 29. With these circuits once closed, 5 the latch motor unlocks the track switch. The limit switch of this motor being thrown at end of travel of locking bolt, opening circuits 2 and 3 and momentarily closing circuit 4 by means of contact fingers 46 and 10 ratchet 48. This closes contactors 60 and 61 which completes circuit 5, holding contactors 60 and 61 closed as before.

Because of the new position of the track motor limit switch we have a new control 15 circuit, which we will designate as circuit 6^B.

This circuit is used to close contactors 138 and 139 by means of magnet coils 174 and 175, the flow of current being from 63 through 68, 69, 164, 165 and 176 to the point 20 177 where the circuit divides, the two branches uniting again at the point 178. The first branch is from 177 through contacts 179 and wire 180 and magnet coil 175 to 178. The second branch is from 177 25 through wire 181, contacts 182, wire 183, magnet coil 174 and wires 88 and 89 to 178. From 178 the circuit is through wires 90 and 91 to terminals 83.

With contactors 60, 61, 138 and 139 closed, 30 current can flow from positive terminal 30 through 60, 95, 121, 107, 138, 111, 51, 110, 109, 139, 113, 114, 115, and 61 to the negative terminal 38. This completes the circuit hereinafter designated as circuit 7^B, 35 and allows current to flow through armature 51 in the reverse direction to that in which it flows when circuit 7^A is completed; hence the direction of the rotation of the motor is reversed and it moves the track 40 switch in the reverse direction, thus closing the main line track, the motor being accelerated by the four branches of circuit 8.

At the limit of travel of the track switch, the track motor limit switch is thrown over 45 to its original position, thus opening circuits 5, 6^B, 7^B, 8 and M-B and momentarily closing circuit 9, which closes circuits 2 and 3 operating the latch motor to run the latch bolt into place. At the end of travel 50 of the latch bolts the operation of the limit switch 36 trips off circuits 2 and 3, leaving the apparatus in its original condition in every particular.

Circuit 1 comprises a momentary contact 55 circuit which serves to start the sequence of operations by energizing the relay solenoids 21 and 22, the operation being automatic from the time until the completion of the sequence.

60 Circuit 2 is the relay holding circuit which keeps the relay contacts 28 and 29 closed after circuit 1 has been broken.

Circuit 3 is the latch motor circuit, including the field magnet winding 40, which 65 unlocks the movable track section. At the

limit of the latch bolt travel the limit switch 36 is thrown, opening circuit 2, and consequently circuit 3, which then includes field magnet winding 173 instead of 40, causes rotation in the reverse direction when circuit 3 is again closed and vice versa. 70

Circuit 4 is a momentary contact circuit closed by the operation of the limit switch 36 at the end of the unlock interval. This circuit is not closed, however, at the end of 75 the lock interval of operation of the motor. The purpose of this circuit is to close contactors 60 and 61 by energizing magnet coil 54.

Circuit 5 holds contactors 60 and 61 closed 80 after being first closed by circuit 4. This circuit includes coil 54 and the track motor limit switch which breaks the circuit by allowing contactors 60 and 61 to open. This is the main control circuit for the track 85 motor.

The following circuits, M-B, 6^A, 6^B, 7^A, 7^B and 8 are energized only when contactors 61 and 60 are closed.

Circuit M-B includes the brake magnet 90 coil 81, which releases the brake, thus allowing the track motor to operate freely.

Circuit 6^A is closed when contacts 60 and 61 are closed only for one position of the track motor limit switch. The position of 95 the limit switch is determined by the previous direction of rotation of the track motor, therefore, whenever circuit 6^A is complete, closing contactors 86 and 78, the track motor will operate to swing the track section in a predetermined direction. 100

Circuit 6^B is similar in every respect to circuit 6^A, except that it closes contactors 138 and 139, thus operating the track motor in the reverse direction and returning the 105 track section to its original position.

Circuit 7^A is the main power circuit to drive the track motor which swings the track section from its original position. Control circuit 5 and 6^A provide this motor 110 circuit by closing contactors 60, 61, 86 and 78.

Circuit 7^B is formed when control circuits 5 and 6^B close contactors 60, 61, 138 and 139, thus completing the track motor circuit again, the current flow through the armature is reversed and the track section 115 returned to its original position.

Circuit 8 is a track motor accelerating control circuit consisting of four branches, 120 closing in order 1, 2, 3 and 4, which in turn close contactors 118, 119, 120 and 121 in the same order. The automatic closing of the several branches of this circuit is accomplished by means of the current limit relay 125 coils 93, 101, 99 and 97, which control the movement of their respective plungers 122, 123, 124 and 125, closing in succession contacts 126, 127, 128 and 129.

Circuit 9 is closed momentarily by con- 130

tact segments 166, making contact with contactor fingers 167 and 168 as the track motor limit switch is thrown from one position to another. The object of this circuit is to 5 close circuits 2 and 3 by means of the relays 21 and 22, thus operating the latch motor so as to lock the track switch in position at either extremity of its travel. It will also be noted that circuit 1 serves to unlock the 10 track switch in each case.

In order to prevent the closing of the contactors accidentally, or in the wrong order, the system includes mechanical interlocks (not shown in diagram) between contactors 15 86 and 138, also between 78 and 139, making it impossible even manually to close contactors 138 and 139 when 86 and 78 are closed, nor can 86 and 78 be closed when 138 and 139 are closed. This eliminates an element 20 of danger due to accidental closing of the wrong contactors.

In addition to these mechanical interlocks, it will be evident from a study of the diagram that the top contacts 182, 84, 179 and 25 76 of the disk interlocks controlled mechanically by the contactors 86, 138, 78 and 139, respectively provide an electrical interlock arrangement through the control circuits as follows:

30 Contactors 86 and 78 can be closed electrically only when 138 and 139 are open and therefore contacts 84 and 76 closed, (by the adjustable insulated copper disk 84' shown) likewise 138 and 139 can be closed only when contactors 86 and 78 are open, therefore contacts 182 and 179 closed.

To insure complete closing of contactors 35 86 and 78 or 138 and 139 in their turn before the starting resistance, grid sections 103, 104, 40 105 and 106 are cut out by means of the control circuits sections of circuit 8, contacts 148 and 146 in series must both be closed before circuit 8 is complete in the first case, and contacts 184 and 185 are required to 45 complete it in the second case.

The object of the current limit interlocks, the operation of which has been described, is to insure automatic acceleration of the 50 large track motor in minimum length of time, keeping the starting current always within the overload limit for the motor under consideration.

In case of flashovers, short circuits or 55 overloads, the motor is protected by means of a current limiting relay consisting of a series coil 26, plunger 186, carrying the insulated copper disk 187, normally closing contacts 117. The relative relation between coil 26 and plunger 186 is adjustable so the 60 device may be set for various ultimate current strengths. When the current through coil 26 exceeds the predetermined value, the attraction between the plunger and coil is great enough to raise the plunger and break 65 circuit 5, which allows contactors 60 and 61

to open and break the main motor and contactor circuits connected between terminals 63 and 83. To start the operation of the track motor again, it is necessary simply to manually close contactors 60 and 61. 70

An inspection of Figs. 3 and 4 will make obvious the operation of this control system when applied to the turntable or draw span.

It is obvious that changes in the precise arrangement of the various electrical devices 75 herein described and shown may be resorted to within the scope of the following claims.

What we claim as new, and desire to protect by Letters Patent, is:—

1. An electrical control for a railroad 80 track section, comprising a motor, devices connected therewith for locking and unlocking said track section, a switch to start said motor whereby it will unlock said track section, a limit switch to stop said motor, another motor adapted to move said track section after it is unlocked, means for accelerating the speed of said last named motor and means adapted to start said first named motor in a reverse direction to lock said 85 track section after it has been moved.

2. The combination with a movable track section of locking means for said track section, a latch motor for actuating said locking means, means for moving said track section, 90 a motor for actuating said track moving means, a circuit connected with said latch motor, a closing circuit for said latch motor circuit, contact mechanism operable at a distance from said track section for said closing circuit, a limit switch for breaking said latch motor circuit after said latch motor has made a predetermined number of revolutions, a circuit for said track operating motor, said circuit being adapted to be closed by said latch motor limit switch, a track motor limit switch adapted to break said track motor circuit and close said latch motor circuit at the end of a predetermined 100 number of revolutions of said track motor to reverse said latch motor and means for causing successive operations of said track motor to be in reverse directions. 105

3. The combination with a movable track section having two operative positions, of 110 means for locking said track section in either of said two positions, a latch motor for driving said locking means, means for moving said track section between said two operative positions, a track operating 115 motor for said track moving means, and a series of electrical circuits, the first of which is adapted to be energized by manually closing a switch and the remainder of which are adapted to be successively 120 closed automatically to energize said latch motor whereby it will unlock said track section, thence to energize said track motor whereby it will move said track and thence to energize said latch motor whereby it will 125 130

be driven in a reverse direction to lock said track.

4. An electrical control for a movable track section of the class described comprising a momentary contact circuit, a relay holding circuit adapted to be closed by said momentary contact circuit, a latch motor circuit adapted to be closed by said momentary contact circuit and maintained in a closed condition by said relay holding circuit, a latch operating motor connected with said latch motor circuit and adapted to control the locking and unlocking of said track section, a limit switch connected with said latch motor to break the said latch motor circuit at the end of a predetermined number of revolutions of said latch motor, a track operating motor for moving said track section, a circuit connected therewith and adapted to be closed by said limit switch at the same time that said latch motor circuit is broken, a brake for said track operating motor, accelerating circuits for said track operating motor, a track motor limit switch for breaking the circuit to said track operating motor and a circuit connected with the said latch operating motor and adapted to be closed by said track motor limit switch to start said latch operating motor in a reverse direction and lock said track section after it has been swung from one position to another.
5. The combination with a movable track section of means for locking said track section in a fixed position, a latch operating motor for actuating said locking means, a track operating motor for moving said track section from one position to another, an electric circuit connected with said latch operating motor and adapted to be closed to actuate said latch operating motor and unlock said track section, a limit switch to

break said latch operating motor circuit at the end of a predetermined period of action of said latch operating motor, an electric circuit connected with said track operating motor for energizing the same, said circuit being adapted to be closed by said latch operating motor limit switch when said latch operating motor circuit is broken, a track motor limit switch adapted to break the circuit to said track motor after a predetermined number of revolutions of said track motor and another circuit connected with said latch operating motor and adapted to be closed by said track motor limit switch to rotate said latch operating motor in a reverse direction and lock said track section.

6. The combination with a movable track section, having two operative positions of means for locking said track section in either of said two positions, a lock motor for driving said locking means, a track motor adapted to swing said track section from one to the other of said positions, circuits for said latch motor, a limit switch for said latch motor circuits, circuits for said track motor, contactors in said track motor circuits, certain of said contactors being adapted to close said circuits and drive said motor in one direction and others of said contactors being adapted to close said circuits and drive said track motor in a reverse direction and safety devices for preventing the closing of said contactors out of their proper order.

Signed by us at Seattle, Washington, this 29 day of May, 1918.
